CHEERLEADER DOLL

Joyce McClanahan and Dawson G. McClanahan, both of
4 Sayers Drive, Williamstown, Ky. 41097

Filed July 1, 1974, Ser. No. 484,718

Term of patent 14 years

Int. Cl. D21—01

U.S. Cl. D34—4 R

FIG. 1 is a front elevational view of a cheerleader doll showing our new design;

FIG. 2 is a right side elevational view showing our new design, the left side elevational view being substantially a mirror image thereof; and

FIG. 3 is a top plan view showing our new design.

We claim:

The ornamental design for a cheerleader doll, substantially as shown and described.
